UNITED STATES PATENT OFFICE.

FRANK B. FALKNER, OF WILKINSBURG, PENNSYLVANIA, ASSIGNOR TO WESTINGHOUSE ELECTRIC & MANUFACTURING COMPANY, A CORPORATION OF PENNSYLVANIA.

RADIO TUNING SYSTEM

Application filed May 6, 1926. Serial No. 107,097.

My invention relates to systems used for the reception or amplification of radio signals and it has particular reference to a tuning device used for either of these purposes.

It has been very often noted when receiving radio signals, particularly those at very high frequencies, that the frequency being received seems to shift relatively slowly at irregular intervals.

This irregular shift in frequency is very detrimental, however, to good reception, especially when use is made of the principle of regeneration to bring extremely weak signals up to good audibility. As is well known, regeneration increases the sharpness of tuning to a marked extent, and for this reason, in receiving short wave signals on a regenerative system, the shift in frequency referred to above gives the effect of fading.

The use of extremely high frequencies is becoming of increasing importance both for long distance point-to-point communication and for relaying. When used for the latter purpose, it is of paramount importance that none of the incoming signals be missed.

It is accordingly an object of my invention to provide a receiving system which will compensate for shifts in frequency of the transmitted signals.

Another object of my invention is to construct a regenerative receiver that shall in some respects operate as though it were broadly tuned.

A still further object of my invention is to devise means which may be introduced into any tuned circuit of an amplifier to give the effect of broad tuning without introducing a damping factor.

A further object, broadly speaking, is to devise a radio receiving system which will, to some extent at least, offset the effect of fading.

In the preferred form of my invention, I attain these objects by providing a circuit which may be partially tuned to the exact frequency at which the signal is expected to be received and, in addition to the arrangements required for this preliminary tuning, I provide means for continually shifting the resonance point of the circuit over a predetermined range. My invention contemplates inserting in one of the controlling tuned circuits of the receiving system, a variable reactor such as a condenser or an inductor

and causing the value of this reactor to continuously and automatically change through a definite cycle.

This cycle is so chosen that the tuning of the circuit varies through the range of the shift in frequency which has been found by experiment to prevail at the particular location of the receiving system.

The rate at which the tuning changes is adjusted until it is above the frequency of the highest audio component of the incoming signal.

This variation in the tuning serves to broaden the resonance curve of the circuit thus equipped, or rather continually shifts the sharp resonance point over a narrow band of frequencies.

The circuit, while exhibiting some of the qualities of a damped circuit, is, at the same time sharply tuned to a definite frequency at every instant, depending on the instantaneous value of the variable element.

I am thus enabled to get the effect of a broadly tuned circuit without the disadvantages attending the use of damping means and the consequent loss of signal strength entailed thereby.

For a more complete understanding of my invention and the principles underlying its operation, reference is made to the drawing accompanying this specification and forming a part thereof, in which

Fig. 1 is a diagrammatic view of a preferred form of my invention when employed with a regenerative receiver, while

Fig. 2 is a similar view of a modification.

Referring now specifically to Fig. 1, a complete single-tube regenerative receiver is indicated diagrammatically in order to more satisfactorily explain the operation and function of the system of my invention.

An antenna 1 is connected through an inductance 2 and a variable condenser 3 to ground 4. Coupled inductively to inductance 2, is another inductance 5, shunted by a tuning condenser 6, and connected at one side through a grid condenser 7 and a grid leak 8, to the grid 9, of a vacuum-tube device 10. The other side of this inductance 5, is connected to the filament 11 of the tube 10 at the point 12. Connected serially between the plate 13 and the filament 11, are a B battery 14, a pair of phones 15 shunted by a by-pass condenser 16, and a tickler or feed-back inductance 17, which lat-

ter is variably coupled to the inductance 5. The tube 10 is provided with the usual A battery 18 and control rheostat 19. The elements so far described are those customarily included in the usual type of single-tube regenerative receiver.

Shunted across the input inductance 5 of the tube is an additional condenser 20, the movable element 21 of which is geared or 10 otherwise connected to a motor 22 or to an analogous device. This motor is provided with a source of current 23, and is arranged so that its speed may be adjusted to any point desired.

15 When it is desired to receive a radio signal on a definite wave length, the small variable condenser 20 is first adjusted by hand to a point where one-half of its total capacity is included in the circuit. The condenser 6 is 20 next adjusted until the circuit comprising inductance 5, condenser 6, condenser 20 and the capacity existing between grid 9 and filament 11, is tuned exactly to the incoming 25 frequency. The antenna ground circuit is also tuned by means of the adjustable condenser 3 and the coupling between inductance 2 and inductance 5 is adjusted to that point which gives the best selectivity. The coupling between the feed-back inductance 30 17 and the inductance 5 is also adjusted to the optimum point and if necessary, the circuit as a whole is retuned. This process of tuning is merely indicative of the steps usually involved in tuning a regenerative 35 receiver.

Assuming now that the circuit is adjusted so as to receive the desired signals with the best audibility, a motor or other means 22 is started and its speed is adjusted to vary 40 the condenser 20 between its minimum and maximum capacity at a rate above audibility. The size of the condenser 20 is so chosen that its maximum capacity when introduced into the circuit, serves to tune such circuit 45 to resonance with the lowest frequency to which the received signal varies, and when its capacity is a minimum, the circuit is then in resonance with the highest frequency to which the incoming signal shifts. The maximum 50 value of this condenser 20 can only be determined by experiment, but in any event, it is comparatively low.

As stated above, the incoming signal tends 55 to shift its frequency at irregular intervals and it is obvious that if a circuit were constructed to tune broadly over the whole range of frequency covered by the incoming signal, none of the signals would be lost by reason of these shifts. As is well known, 60 however, in order to construct a circuit which tunes broadly, it is customary to introduce a damping factor. This damping causes losses and renders the system as a whole much less sensitive to weak signals.

65 By means of my invention, however, I

am enabled to shift the tuning of the circuit over the same range of frequency through which the incoming signal passes, yet at the same time, I introduce no additional damping means into the circuit. Inasmuch 70 as this change in the tuning is preferably made at a super-audible frequency, the reception of signals is not interfered with. At any instant, the circuit is sharply tuned to a definite frequency and it is only by reason of the fact that the successive tuning points of the circuit extend over a frequency 75 band that the effect of broad tuning is obtained.

Referring now specifically to Fig. 2, a so circuit quite similar to that of Fig. 1 is diagrammatically shown. The only difference between the circuit shown in Fig. 2 and that shown in Fig. 1 is in the type of variable reactor employed. Instead of the variable 85 condenser 20 shown in Fig. 1, I show a small variable inductor 24, in series with inductance 5 which inductor is arranged to have its value continually and rapidly varied.

The effect of this variable inductor is essentially the same as though a condenser were used as in Fig. 1, but in some cases, it may be found that signal strength, when employing the circuit of Fig. 2, is somewhat better than when employing the arrangement shown in Fig. 1.

Although I have shown my invention as used in connection with a single-tube regenerative receiver, it is not to be considered as limited to such use. Either of the arrangements indicated may be employed with practically any type of a receiver or amplifying circuit. For instance, the resonant receiving circuit of a super-heterodyne system might be equipped with my invention 105 for securing substantially the same result. It is also feasible to apply my invention to the frequency control circuit of the generator used with a superheterodyne receiver, or it might even be applied to one of the intermediate circuits tuned to the beat frequency. These other applications of my invention are given merely by way of example as it is believed to be obvious that it may be applied to practically any tuned circuit involved in a receiver or amplifier when the signals to be received are subject to frequency shifts.

Among the principal advantages resulting from the use of my invention is that the reception of short-wave signals is very materially improved. It has been noted that, when a receiving system is equipped in accordance with my invention such short-wave signals come through with substantially no fading whatever. This result is of very decidedly advantage when these short-wave signals are being used to control the output of a transmitter at a relay station, since it is obvious that in order to secure perfect re- 130

transmission, none of the incoming signals must be missed.

Another advantage lies in the reduction of distortion in the received signals. The exact cause of this distortion is not definitely known but it is quite pronounced when ultra-high frequencies are being received.

Although I have illustrated and described herein certain specific embodiments of my invention, I am fully aware that many other modifications are possible and my invention is not to be limited except in so far as is necessitated by the prior art and as indicated by the following claims.

15 I claim as my invention:

1. In a receiving device, a circuit including tuning means adapted to be adjusted to tune the circuit to any frequency within the range for which the receiving device is intended, and a continuously acting supplemental tuning device so disposed as to continuously and cyclically alter the frequency to which said circuit is tuned, said continuous alteration being a small fraction of the change said adjustable tuning means can

produce and being only as large as the maximum expected unintentional variation in the frequency to be received, the frequency of the cycle of said continuous alteration being above audition.

2. The method of preventing loss of signals by a receiving set including a tuned circuit comprising reactors of opposite sign through fading caused by frequency changes of said signals without increasing the resistance of said circuit, which consists in cyclically varying the reactance of the reactor of one sign, said variation having a period above audibility and an amplitude sufficient to include the frequency changes which ordinarily cause fading and insufficient to cause loss of signal when the signal frequency is at its normal value, and simultaneously producing an indication of said signals.

In testimony whereof, I have hereunto subscribed by name this first day of May, 1926.

FRANK B. FALKNOR.
